Margaret F. Haas, New York, N. Y.

Application September 24, 1952, Serial No. 311,275

3 Claims. (Cl. 41—13)

The present invention relates to a novel and improved ornamental member simulating flowers, immortelles, or the like, and to a process of forming such members.

Objects and advantages of the invention will be set forth in part hereinafter and in part will be obvious herefrom, or may be learned by practice with the invention, the same being realized and attained by means of the instrumentalities and combinations pointed out in the appended claims.

The invention consists in the novel parts, constructions, arrangements, combinations and improvements herein shown and described.

The accompanying drawings, referred to herein and constituting a part hereof, illustrate embodiments of the invention, and together with the description, serve to explain the principles of the invention.

Of the drawings:

Figure 1 is a fragmentary side elevation showing steps in the process of making the ornamental members of the present invention;

Figure 2 is a front elevation of a typical and illustrative form of the ornamental member of the present invention in a partially completed stage;

Figure 3 is a similar view of a slightly different form of the invention;

Figure 4 is a fragmentary side elevation showing steps in a modified process of the present invention; and

Figure 5 is a front elevation of a different form, as produced by the process illustrated in Figure 4.

The present invention has for its object the provision of a novel and improved process for the formation of ornamental members simulating flowers, immortelles or other objects and which may be used in various ways as ornaments on millinery, coats, dresses and other garments, Christmas trees, window decorations or as immortelles. A further object of the invention is the provision of a novel and improved ornamental object which has a distinctive appearance, is durable and may be made in a wide variety of appearances merely by changing the arrangement, the number, the colors, or the sizes of its component parts.

According to the present invention, there is provided a process of forming ornamental members, as well as ornamental members formed thereby, which comprises knotting a strand or strands of relatively heavy and relatively stiff flexible filament, the knots being at regularly spaced points, and providing portions of the strand or strands which extend beyond the knots, these portions being longer than the space between adjacent knots, the ends of the strand or strands being brought together and fastened with the series of knots arranged in a curved series between the ends of the strands, and with the extending portions of the strands at the knots projecting outwardly from the series either as individual loops or as the cut ends formed from such loops.

Referring now in detail to the accompanying drawings which show the various steps of the process, as well as typical, illustrative and preferred embodiments of the invention, the ornamental member is formed from a long length of plastic filament 10, usually from about 0.4 to about 1.5 mm. in diameter and of any desired color, and preferably about 0.8 mm. in diameter, the plastic filament having sufficient stiffness so that when it is coiled into loops about $\frac{1}{4}$ inch in diameter or less it is relatively rigid and considerable force is necessary to distort the curved shape of the loop. Many different plastics are suitable but I prefer to use heavy filament vinylidene chloride

2

("Saran"), vinyl chloride-acetate copolymer ("Vinylite"), plasticized cellulose acetate or nylon.

As shown in Figure 1, the filament is knotted by forming a coil 12 and a loop 14 and by pushing the loop 14 through the coil 12 and placing the loop over a pair of parallel rigid members 16, such as heavy knitting needles, after which the filament is drawn tight to form a knot 18 at the ends of the loop. Thereafter the loop is pushed along the pair of knitting needles, and the operation of forming loops and knots and positioning the loops on the needles is repeated until a considerable number, usually from seven to fifteen, have been formed with the knots 18 closely adjacent each other. When a sufficient number of loops and knots have been formed, with the loops 14 relatively large compared to the spacing of the knots 18, the end of the strand of filament is cut, and the loops 14 may be slid off the knitting needles 16. It is in this operation, that it is particularly useful to have used two knitting needles, as it is found that one needle may be easily withdrawn from a pair of them, while the withdrawal of a single needle where only one has been used is somewhat troublesome.

When a relatively large number of loops 14 have been formed, as in making a larger ornament, it is often desirable to stiffen the eventual ornament by means of a relatively stiff piece of wire which may be inserted along the length of the two needles 16 before removal of the loops 14, and the narrow groove between the two needles forms a convenient slot for this insertion of the wire member 20.

After the loops have been removed from the needles, the opposite ends 22 of the strand 10 are brought together, thereby forming a generally circular row or series of loops 14, as shown in Figure 2, and the two end portions 22 are placed parallel to each other and bound fast to each other to secure them in looped position. This binding may be by means of a separate piece of wire coiled around the ends 22, but where the wire 20 has been used to stiffen the ornament, the ends of the wire 20 may be brought together adjacent to the ends 22 and may be coiled around the strand ends 22, as at 24 to hold the strand ends as well as the wire ends together to secure the looped series of loops 14 and knots 18 in the form shown. Then, the stem may be wrapped by means of a narrow strip of adhesive tape 26.

Figure 3 illustrates a further development of the present invention in which two ornaments of the type shown in Figure 2, but of different sizes are combined into a single ornament, and a small central portion 28, resembling a pistil, on a stem 30 may be assembled with the ends 22 by means of the coiled ends of the wire 20. However, in Figure 3, the smaller loop of knots 18 is small enough so that the strengthening wire loop member 20 is not needed and has been omitted, although the entire structure is secured together by means of a coiled wire 32 which is eventually wrapped with the adhesive tape 26 to form the completed ornament.

The monofilament 10 is shown in Figure 3 as being of one color on the outer or rear series of loops 14, and of a different color on the smaller looped component at the front of the assembled ornament. Additional variety can be introduced by using a plastic filament which has a longitudinal core of a relatively bright color and is surrounded by a somewhat transparent sheath of a different color or by a sheath which is substantially colorless and transparent, the two layers being handled as a single filament, with the sheath fitting snugly on the core and sometimes bonded thereto.

Figures 4 and 5 illustrate a modified form of the present invention and as shown one or more strands 10 of the plastic filament are knotted and looped on the needle member 16 to form a loosely spaced series of knots 38 which are rightly drawn about the needle. When a sufficient number of the knots have been formed, the knots and loops 40 being substantially uniform, the loops are cut, as shown in the lefthand portion of Figure 4, thereby providing relatively long, free ends 42 of the filament 10, the ends being substantially longer than the spaces between adjacent pairs of knots 38.

This cutting of the loops may be carried out by drawing a razor blade or other sharp knife across the upper face

of the needle 16 on the side opposite the row of knots 38.

If desired a relatively fine and stiff piece of wire 46 may be passed through the loops 40 and drawn tightly into the form shown in Figure 5, with its ends brought together and wrapped around stem portion 44 in a manner similar to the embodiment of Figures 1 and 2. The use of this wire is, however, restricted to instances where extreme rigidity is desired since otherwise this form of my invention possesses sufficient rigidity without the use of the wire.

After assembling the strands as shown in Figure 5 with the ends thereof brought together in parallel relation and the knots 38 disposed generally in a circle the cut ends 42 of the filament stand out away from the knots in an irregular manner, so as to provide a pleasing and ornamental appearance to the entire assembly.

The ornamental members, simulating flowers, thus produced (Figure 5) are fastened, with fine wire or otherwise, to natural twigs or other fitting supports.

If desired the strands 10 may be of different colors, but preferably two such strands 10 are used, and ordinarily they would be of the same color.

The present application is a continuation-in-part of my prior filed application Serial No. 274,387, filed March 1, 1952, now abandoned.

The invention in its broader aspects is not limited to the specific mechanisms shown and described but departures may be made therefrom within the scope of the accompanying claims without departing from the principles of the invention and without sacrificing its chief advantages.

What is claimed is:

1. An ornamental member comprising a continuous strand of flexible filament, said strand having a series of

spaced slip knots positioned between the ends of said strand and looped strand portions extending outwardly from each of said knots, said strand having its ends positioned together whereby said series of knots are formed into a substantially circular closed ring having said looped strand portions extending outwardly therefrom, and a relatively stiff wire member encircling said series of knots and interwoven with said looped strand portions to maintain them in a substantially flat position, said wire member having its ends coiled about said strand ends to hold said ends together.

2. An ornamental member as described in claim 1 having a substantially smaller and similar ornamental member centrally positioned and secured thereto, and a simulated pistil centrally positioned and secured to said ornamental members.

3. An ornamental member as described in claim 1 wherein said strand comprises a plurality of strands of flexible filaments and said looped strand portions are severed at their bight.
